DESIGN FOR AN ADVERTISING SIGN

Application filed March 19, 1931. Serial No. 39,169. Term of patent 14 years.

To all whom it may concern:

Be it known that we, RALPH B. BENCKER and BRUCE E. HOWDEN, citizens of the United States, residing at Philadelphia, in the county of Philadelphia and Commonwealth of Pennsylvania, have invented a new, original, and ornamental Design for an Advertising Sign, of which the following is a specification, reference being had to the accompanying drawings, forming a part thereof.

In the drawings:

Figure 1 is a front elevation of the advertising sign, and

Figure 2 is a side elevation thereof.

The heavy dotted lining along the letters and within the supports represents neon tubes.

We claim:

The ornamental design for an advertising sign, as shown and described.

RALPH B. BENCKER.
